UNITED STATES PATENT OFFICE

117,545

DESIGN FOR A HAT

Irwin B. Simon, San Francisco, Calif.

Application April 25, 1939, Serial No. 84,542

Term of patent 3½ years

To all whom it may concern:

Be it known that I, Irwin B. Simon, a citizen of the United States and a resident of the city and county of San Francisco and State of California, have invented a new, original, and ornamental Design for a Hat, of which the following is a specification, reference being had to the accompanying drawing, forming part thereof,

I claim:

The ornamental design for a hat, as shown.

IRWIN B. SIMON.
